UNITED STATES PATENT OFFICE.

EDWIN N. LIGHTFOOT, OF NEW YORK, N. Y.

ELECTRIC RESISTANCE UNIT.

1,046,816.

Specification of Letters Patent. Patented Dec. 10, 1912.

Application filed December 14, 1911. Serial No. 665,788.

To all whom it may concern:

Be it known that I, EDWIN N. LIGHTFOOT, a citizen of the United States, residing at New York, in the county of New York and

5 State of New York, have invented new and useful Improvements in Electric Resistance Units, of which the following is a full, clear, concise, and exact description, reference being had to the accompanying drawing,

10 forming a part of this specification.

My invention relates to electric resistance units. These units are particularly adapted to be employed in electric heating appliances.

15 In practice it is difficult to firmly support a resistance of small cross section and at the same time provide for maximum radiation and efficiency within a given space. Resistance units have been made wherein the 20 resistance is convoluted and is supported by a rod which passes through its convolutions. In order to provide for rapid radiation of the heat and to obtain great efficiency, the resistance is so formed that it merely engages the rod at certain points, other points 25 of the resistance being spaced from the rod.

The object of the present invention is to so form the resistance that it will be firmly supported by the rod without impairing its 30 efficiency. To attain this end, a convoluted resistance in which each convolution is triangular in form, is supported by an insulating rod which passes through the convolutions. The three sides of each convolution 35 engage the supporting rod substantially tangentially so that each side is firmly held upon the supporting rod by its two adjacent sides. The convolutions are of such form and size that merely a small portion 40 thereof engages the rod. Each convolution is thus firmly maintained in position and at the same time the resistance is allowed to rapidly radiate the heat and obtain maximum efficiency. The resistance may be 45 made of any suitable material and is preferably in the form of a wire, ribbon, or strip. The structure which the invention provides makes it possible to readily employ a resistance of minute cross section.

50 In practice the invention may assume various forms. Several units embodying the invention are illustrated in the accompanying drawings. They have been selected merely for the purpose of illustration and 55 therefore it will be understood that other

structures which attain the purpose in view are within the scope of the invention.

The views in the drawings are as follows:—

Figure 1 shows a side elevation of one 60 form of unit; Fig. 2 shows an enlarged detail view of one form of terminal connection for the unit; Fig. 3 shows a modified form of terminal connection; Fig. 4 shows a side elevation of another form of resistance 65 unit. Fig. 5 shows a detail view of a portion of the same. Fig. 6 shows a unit mounted in a support. Fig. 7 shows a unit mounted in a modified form of support. Fig. 8 shows a unit mounted in another 70 modified form of support. Fig. 9 shows a perspective view of one of the supporting rods shown in Fig. 8. Fig. 10 shows one means of connecting adjacent resistance units. 75

In the constructions shown for purposes of illustration I have illustrated a plurality of forms of my improved resistance unit, including a slotted, bent, reflexed or otherwise formed strip of resistance material 1 80 having the ends of its adjacent convolutions spirally arranged and extending in different angular directions; an insulating support 2 extending through said convolutions and acting as a means for insulating and spacing the convolutions of the same, and at the same time as a means for supporting the 85 same in the desired relation.

In Figs. 1 to 3 inclusive I have shown an electric resistance unit formed of slotted 90 resistance ribbon made of any desired resistance material. This resistance ribbon has its adjacent convolutions bent in opposite directions so that a substantially triangular shaped section of resistance material is 95 formed in which parts of the convolutions of resistance material form the sides of the triangle. For instance, taking the convolutions 3 and 4 shown in Fig. 1, when the resistance material is in the form of the 100 slotted strip the convolution 4 lies above the convolution 3, as shown in Fig. 2. When it is desired to shape the unit as shown in Fig. 1, the convolution 4 is forced over to the right, leaving the convolution 3 at the left. 105 The upper half of the convolution 4 is then brought again to the right and the adjacent halves of the convolutions are successively moved to the right and left in this manner to provide a resistance section of the shape 110

shown in Fig. 1, wherein the unslotted ends of the resistance material extend in a plurality of different radial positions. Thus it is seen that in this form of unit the ends of 5 the convolutions are arranged in three rows, and that a central opening is provided in which the insulating support may be inserted.

While in the drawings the projecting 10 ends or points of the convolutions are shown in straight rows or in alinement it should, of course, be understood that this regularity is not necessary as the projecting ends or points of adjacent convolutions 15 might be arranged at relatively different angles if desired.

The insulating support 2 may be formed of any suitable insulating material of a type which is adapted to serve not only as a support for the resistance material, but also as 20 a means for insulating the same. In a preferred form, I use quartz-glass, magnesite or the like, in making up this support, since such materials are capable of standing up 25 under very high temperatures. In constructions designed to operate at lower temperatures I may use an insulating material having a lower melting point. If desired, I may use ordinary glass as the material for 30 the insulating support. In the use of such a material I find that I am able to provide a support of great stability, since when the insulating material is brought to a high 35 temperature it is melted slightly so that the resistance material embeds itself more or less in the same, forming a substantially unitary device.

In Fig. 2 I have illustrated an end connection or terminal connection which may 40 be used with a resistance material of the type shown in Fig. 1. As shown in this construction, the end 5 of the resistance material may be left unslotted and may be bent over as at 6 along a substantially diagonal line to form two flaps. A perforation 45 7 may be provided near the free end of the unslotted portion, and a plurality of registering perforations 8 may be provided in the bent-over portions. When it is desired 50 to provide a terminal connection for the unit of such a construction, all that it is necessary to do is to fold together the ends in which the perforations 7 and 8 are made, so that they lie in substantially parallel 55 planes, as shown in Fig. 1, and then connect them by any suitable binding screw or other suitable device 9, to which a line conductor may be attached.

In Fig. 3 I have illustrated a further 60 modified form of terminal connection. As shown in this construction, instead of leaving the end unslotted, as shown in Fig. 2, I may clip the end of the unit adjacent to the end of the slotted portion and bend one or 65 more turns of the slotted portion around

the insulating support 2, so that it may be readily inclosed in a suitable conducting clip 10 having perforations in its flaps 11 arranged to receive a suitable binding screw 12. It is to be noted that in this construction, instead of having the unslotted end of the resistance material form the clip for holding the binding screw, I provide a separate holding clip for the binding screw.

In a preferred form when I use a reflexed 75 resistance material, I slightly bend out or round the portion of the resistance material between the ends of the convolutions as at 13, in order to provide a better contact with the support. As shown in this construction 80 the terminal connections may be, if desired, the same as those shown in Fig. 3, the ends of the reflexed material being inclosed between the clips 10.

In Figs. 4 and 5 I have illustrated a further modified form of resistance material which I may use, if desired. This resistance material is made up from a resistance material in the form of a tape which may be wound on a mandrel in the form of a helix, 90 and then flattened so that it assumes a substantially triangular form, as shown in these figures. If desired, the terminal connections for the same may be substantially the same as those I have shown in Fig. 3, 95 although in this instance since there are no slotted convolutions the last convolution of the helix may be bent over substantially at right angles and brought up along the tube before it is brought around the tube, as 100 shown in that figure.

In Fig. 6 I have illustrated a preferred form of construction wherein I employ two or more resistance units. The insulating supports 2 carrying these resistance units 105 are preferably made up in the form of tubes loosely fitted upon a plurality of metal rods 14 and 15. In the construction shown I have illustrated two rods 14 and two rods 15, the rods 14 and 15 being fixed in a suitable frame 16 preferably formed of insulating material. In the construction shown the rods of each set 14 and 15 do not extend entirely through the two insulating tubes 2, but enter the tubes from each end and are 115 shorter than the tubes, so that there is a space between the inner ends of the rods which, upon the expansion or contraction of the same, permits them to move freely to adjust themselves upon the changes in temperature. In constructions wherein I employ two or more resistance units I preferably so arrange the electrical connections 120 for the units that the rods 14 and 15 may serve as the terminals for the device. In 125 this construction the ends of the resistance material are preferably attached to the conducting rods 14 and 15 as at 17, by any suitable means, so that they engage with the metal rods in such a manner as to make 130

the metal rods in such a manner as to make 130

a good electrical contact. If desired, they may be spot-welded thereto. The outer ends of one set of rods are preferably electrically connected as for instance by a conductor 18, which may extend between suitable binding screws 19 carried upon the ends of the rod in any suitable manner as by threading, if desired. The opposite ends of the other set of rods may be provided with similar binding posts 19 in order that they may be connected to the line conductors.

In Fig. 7 I have illustrated diagrammatically a preferred manner of mounting my resistance unit in a support. The insulating support 2, as heretofore described, is preferably made hollow and tubular in form so that it may receive a rod 22. This rod 22 in this construction preferably extends entirely through the tube 2, upon which it is loosely fitted. In a preferred form, one end of this rod is fixed, as by embedding if desired, in an insulating base 21, while the other end is free to move in its support, as for instance in a second insulating base 20. The two base members 20 and 21 may obviously be in the form of a frame, although I have not shown the entire frame in the drawings. In a preferred form the upper end of the rod 22 is free to move in an opening in the base 20, as shown, so that when the rod is heated by the passage of current through the resistance material, the rod may expand freely and may contract when the current is cut off. It is obvious that in this construction the resistance material may be connected in circuit in any suitable manner.

In Fig. 8 I have illustrated a preferred form of connecting a plurality of resistance units. In this construction the insulating tubes are mounted upon two short rods, which like the rods shown in Fig. 8 do not extend entirely through the tubes. In the preferred form these rods are formed in a substantially U-shape, as shown at 23, the arms of each U-shaped rod being arranged to fit within the ends of adjacent insulating tubes. In a preferred form, the U-shaped members 23 are carried upon insulating bases 24, which may form part of a frame, if desired. One or more of the rods 23 may be provided with loops 25 intermediate to their ends (Fig. 9), so that they may be attached to a portion of the base 24 by means of clamping bolts 26. In a preferred form the ends of the adjacent units are brought up to these clamping bolts 26, as shown in Fig. 10, so that the circuit of the device extends in series successively through each unit as shown in that figure. If desired, the lower rods 23 may be embedded in the lower base 24, and any number of units and supporting rods may be used.

In Fig. 10 I have illustrated a further

preferred form of connecting the ends of adjacent units. As shown in this construction several units may be made up from one piece of resistance material, and this resistance material may be so formed that a connecting strip 27 of resistance material connects the units at the desired points, when they are mounted on their supports. Thus I am able to provide any desired number of units which are formed integral with each other, and thus avoid the loss of time and expense incident to connecting the several units together. It is obvious, however, that where it is advisable to use shorter strips of resistance material the ends of these strips may be connected to each other by any suitable means, as for instance by means of spot-welding, as indicated in dotted lines at 28 in Fig. 10.

If desired, instead of using an insulating tube formed of glass I may instead, for certain purposes, coat the metallic supporting rod with a covering of enamel or use a soft glass which becomes fixed to the rod, and in this manner produce a unit wherein the insulating sheath is integral with the support, the support being movable if desired. When enamel is used, this enamel may, if desired, have a higher melting point than the running temperature of the unit, so that the unit will not embed itself in the insulating material to such an extent as to cause a short circuit. For some uses, however, I find it advisable for the resistance material to embed itself to a certain extent in the insulating support, since this gives a more stable support and a more unitary structure. For some purposes I may, if desired, coat the rod with a covering consisting of two coats of enamel, the outer of which has a lower melting point than the inner, so that the temperature at which the resistance is embedded, while sufficiently high to soften the outer coat is not sufficiently high to soften the inner coat. Obviously, the resistance material may be embedded to any desired degree in the insulating material.

My improved electric resistance unit is of a type well adapted to use either as a means for dissipating energy or as a means for generating heat for heating purposes. The resistance material may be arranged upon the support in such a manner that the heat radiated is distributed evenly from the unit and is readily absorbed from the same by the atmosphere or the object to be heated. My improved unit may, therefore, be readily adapted to use as a heater for electric heating devices, wherein the devices are adapted to operate at a red heat. Further, by my improved manner of mounting the resistance material upon the insulating support I am able to provide not only a means for effectually insulating the unit in such a manner that the resistance material engages

the insulating support at a large number of points, but I am also able to provide a support which places no strain upon the resistance material. Since the resistance material is supported at a large number of points, and is under no mechanical strain, it will not spring apart or uncoil if its continuity is broken in any way. By my improved construction I am able to provide a unit which may be readily operated at high temperatures without any danger of breaking through the insulation of the device or burning out the same. This is particularly true in those constructions wherein a quartz tube is used. By the provision of my improved means of allowing for the expansion and contraction of the supporting rod for the unit, I am able to effectually prevent any breakage of the unit or any distortion of its support, the insulating support being freely movable when desired upon the rod and the rod itself, when desired, being freely movable in its frame. Where it is not desired to use the device for high temperatures, instead of using the quartz tube I may employ a glass tube or the coatings of enamel which I have mentioned. By my improved manner of mounting the resistance unit or a plurality of these units in a frame, I am able to prevent not only the distortion of the device, due to the contraction and expansion, but I am also able to use the supporting rods for the device as the terminals for the same, and in this manner cut down the number of necessary parts.

Further, a plurality of these units may be formed of a single strip of resistance material, portions of the same being wound on the several units; or, if desired, a plurality of strips of resistance material may be used, the ends being electrically connected as by spot-welding. 40

While I have in this application described several forms which my invention may assume in practice, I do not wish to be limited 45 to these forms chosen for purposes of illustration, but wish rather to cover within the scope of this application all of those forms of my invention falling within its spirit.

What I claim as new and desire to secure 50 by Letters Patent is:—

A resistance unit comprising a supporting rod and a convoluted resistance carried by said rod and having its convolutions surrounding the same, the convolutions of said 55 resistance being triangular in form and each convolution having all three sides thereof engaging said rod tangentially so that each side is firmly held against said rod by its two adjacent sides and each convolution is 60 spaced from said rod except at its points of tangential engagement therewith.

In witness whereof, I have hereunto subscribed my name in the presence of two witnesses.

EDWIN N. LIGHTFOOT.
